UNITED STATES PATENT OFFICE.

MORRIS B. ROSENSTOCK, OF NEW YORK, N. Y.

SANITARY TOILET.

1,005,075.

Specification of Letters Patent.

Patented Oct. 3, 1911.

Application filed June 30, 1910. Serial No. 569,785.

To all whom it may concern:

Be it known that I, MORRIS B. ROSENSTOCK, a citizen of the United States, residing in the borough of Manhattan of the city 5 of New York, in the State of New York, have invented certain new and useful Improvements in Sanitary Toilets, of which the following is a specification, reference being had to the accompanying drawing, forming a part hereof.

This invention has for its ultimate purpose to provide for the complete disinfection of all matter received in the bowl or hopper before it is discharged, and has been 15 developed with especial reference to its application to toilets of railway cars through which germs of disease may be spread over a great extent of territory and in the use of which, therefore, there is special need of 20 complete disinfection before the discharge of the contents.

In accordance with the invention there is provided, in addition to the usual bowl or hopper, a secondary chamber in which the 25 contents of the bowl or hopper are received and in which they are subjected, for a sufficient period of time to produce substantial results, to the action of a suitable germicide or disinfectant, before they are discharged 30 upon the ground. Furthermore, inasmuch as no ordinary germicide or disinfectant, such as it is practicable to use, can penetrate within a reasonable time solid or semi-solid masses, provision is made whereby all 35 such masses are thoroughly broken up and thoroughly mixed with the disinfectant so that the entire contents of the secondary chamber are thoroughly disinfected before they are discharged.

40 The invention will be more fully explained hereinafter with reference to the accompanying drawing, the single figure of which shows, partly in section and partly in elevation, a toilet equipped with the invention.

The toilet itself may be of any suitable kind. The toilet *a* shown in the drawing comprises the usual bowl or hopper or receptacle *b*, the contents of which are temporarily retained by a valve *c* and prevented thereby from passing through the opening *d*. The valve *c*, if used, may also be of any suitable character and is shown as pivoted at one edge and having an arm *c'* which is connected by a link *c''* with an operating lever *e*, so that as the handle of the operating

lever is thrust down the valve is opened. A water supply for flushing purposes is connected with the hopper, as indicated by the pipe *f*, which, in the construction shown, is 60 provided with a valve, as at *f'*, which is connected by a link *f''* with the lever *e*, so that when the handle of the lever *e* is depressed and the valve *c* is opened, water is admitted for flushing out the bowl or hopper *b*. 65 Obviously the toilet may be of the ordinary siphon form in which no valve is employed and the supply of water for flushing purposes may be controlled by any suitable means. The contents of the bowl or hopper 70 *b* are discharged, either directly or indirectly, into a secondary receptacle or chamber *g* which, in the construction shown, is located below the hopper *b*. The chamber *g* is of such capacity as to receive the entire 75 contents of the bowl or hopper *b* and is adapted to retain such contents for a substantial period of time, or until the bowl or hopper *b* is again emptied of its contents. To this end it has an outflow *g'* connected 80 with the chamber *g* at or near the top thereof.

In order that the contents of the chamber *g* may be disinfected therein, there is connected to the chamber *g* a supply of a suitable disinfecting fluid, such as a solution of formaldehyde from which preferably a measured quantity of the disinfectant, proportioned to the capacity of the receptacle or chamber *g*, is delivered to the chamber *g* 85 each time that the contents of the bowl or hopper *b* are discharged into the chamber *g*. In the arrangement shown in the drawing the supply vessel *h*, for the disinfectant fluid, is connected by a pipe *h'* with the 90 chamber *g* and at a convenient point in the pipe *h'* is introduced an ordinary measuring valve *h''* which may be operated by the lever *e*. As it is desirable that the disinfectant be admitted to the chamber *g* after the 95 contents of the bowl or hopper *b* have been discharged into it, the lever *e* is provided on its rear end with a pivoted, spring-pressed cam toe *e'* which yields upon contact with the plunger *h''* of the measuring valve *h''* 100 during the upward movement of the cam toe, or when the valve *c* is being opened, but is held from yielding so as to operate the measuring valve when the lever is being moved to close the valve *c*. The disinfectant 105 is therefore introduced into the chamber *g* 110 so as to act upon the contents of the hopper

which have just been discharged into the chamber and is not carried away with the previously disinfected contents of the chamber *g* which are displaced by the newly received contents from the hopper.

In order that the disinfectant may at once be brought into contact with every particle of the contents of the chamber *g*, so that such contents may be thoroughly disinfected in a reasonably short space of time, there is provided in the chamber *g* a stirrer or agitator *i* which thoroughly and intimately mingles the disinfecting fluid with the contents of the chamber. Obviously the character of the stirrer or agitator may be varied to suit different conditions of use. In the construction represented in the drawing, the stirrer or agitator consists of a spiral web mounted on a vertical spindle *i'* which projects downwardly through a suitable stuffing box in the bottom of the chamber *g* and is driven through bevel gears *i''* and a shaft *i'''* by a small electric motor *i''''*. The stirrer or agitator may be operated continuously, or it may be operated at intervals preferably immediately after the discharge of the contents of the bowl or hopper *b* into the chamber *g*. The operation of the agitator at intervals may be determined by any suitable means. In the arrangement shown, the connections *k*, *k'*, of the motor *i''''* include a suitable battery *k²* and contacts *k³* and *k⁴*, which may be bridged by a switch member *k⁵*. The latter is arranged to slide in contact with the contacts *k³*, *k⁴*, and to keep the circuit closed for such period of time as it is found desirable to have the agitator or stirrer operated. For this purpose the switch member *k⁵* is carried by a plunger rod *l* which has at its lower end a piston *l'* traveling in a spring dash-pot *l''* of ordinary construction, while at the upper end the plunger rod *l* carries a wheel *l'''* with which co-operates a cam *l''''* which may be mounted on the door *m* of the room in which the toilet is placed. Therefore, whenever the door is opened, the circuit of the motor is closed and the agitator is operated for a sufficient period of time to thoroughly mix the contents of the chamber *g*. In this arrangement provision is thus made for the agitation of the contents of the chamber *g* which have already been subjected to the action of the disinfectant for a greater or less length of time, immediately before such contents are discharged through the entrance of a new

charge, and also for the agitation of the contents of the chamber *g* which have just been received from the bowl or hopper *b*.

It will be understood that various changes in details of construction and arrangement of parts may be made without departing from the spirit of the invention, which is not limited to the particular construction which has been chosen for illustration and explanation herein of the nature of the invention.

I claim as my invention:

1. In a sanitary toilet, the combination of a bowl or hopper, a secondary chamber or receptacle into which the contents of the bowl or hopper are discharged and in which such contents are retained for a period of time, means for supplying a disinfectant to said chamber, and means for thoroughly mixing the contents of the chamber with the disinfectant.

2. In a sanitary toilet, the combination of a bowl or hopper, a secondary chamber or receptacle into which the contents of the bowl or hopper are discharged and in which such contents are retained for a period of time, means for supplying a disinfectant to said chamber, an agitator in said chamber and means for operating said agitator.

3. In a sanitary toilet, the combination of a bowl or hopper, a secondary chamber or receptacle into which the contents of the bowl or hopper are discharged and in which such contents are retained for a period of time, means for supplying a disinfectant to said chamber, an agitator in said chamber, means for operating said agitator and means for determining the operation of the agitator at intervals.

4. In a sanitary toilet, the combination of a bowl or hopper, a secondary chamber or receptacle into which the contents of the bowl or hopper are discharged and in which such contents are retained for a period of time, means for supplying a disinfectant to said chamber, an agitator in said chamber, a motor for driving said agitator, a door, and means controlled by the movement of said door for determining the operation of the motor.

This specification signed and witnessed this 29th day of June A. D., 1910.

MORRIS B. ROSENSTOCK.
